(57) CLAIM

The ornamental design for a buffet, as shown and described.

DESCRIPTION

FIG. 1 is a front perspective view of an embodiment of a buffet showing my new design;

FIG. 2 is a front view thereof;

FIG. 3 is a left side view thereof, the right side view being a mirror image thereof;

FIG. 4 is a top view thereof;

FIG. 5 is a front view of an additional embodiment of a buffet showing my new design; and,

FIG. 6 is a left side view thereof, the right side view being a mirror image thereof.

The broken line portions are for illustrative purposes only and form no part of the claimed design.

1 Claim, 6 Drawing Sheets
